R. TACHIBANA

ANNUNCIATOR

Filed March 13, 1924

INVENTOR
R. Tachibana

BY
K. Tachibana, A. T. T. Y. S.

UNITED STATES PATENT OFFICE.

RITUMA TACHIBANA, OF PORT ARTHUR, ONTARIO, CANADA.

ANNUNCIATOR.

Application filed March 13, 1924. Serial No. 699,097.

To all whom it may concern:

Be it known that I, RITUMA TACHIBANA, a subject of the Emperor of Japan, residing at Port Arthur, in the Province of Ontario, Canada, have invented certain new and useful Improvements in Annunciators, of which the following is the specification.

The invention relates to improvements in annunciators and an object of the invention 10 is to provide an annunciator for mounting on an office or house door and which will definitely indicate whether the occupant is in or out, and if out will show the time at 15 which he will be back and to construct such parts for manipulation from the interior of the door.

A further object of the invention is to associate with the indicator a bell which can be rung from the exterior and also to 20 arrange the annunciator so that it has a pleasing exterior appearance and such that it can be installed at comparatively small expense and when installed will be positive in action.

With the above more important objects in view the invention consists essentially in the arrangement and construction of parts hereinafter more particularly described and later pointed out in the appended claims, 30 reference being had to the accompanying drawing in which:

Fig. 1 is an exterior view of the indicator as it appears applied on the door.

Fig. 2 is an interior view thereof.

Fig. 3 is a horizontal sectional view at 35 3-3' Fig. 1.

Fig. 4 is a vertical sectional view at 4-4' Fig. 3.

Fig. 5 is a vertical sectional view at 5-5'

40 Fig. 1.

Fig. 6 is an enlarged detailed vertical sectional view at 6-6' Fig. 5.

Fig. 7 is a sectional view at 7-7' Fig. 4 and showing the key hole slot.

45 Fig. 8 is a reverse view of the rotary sign. In the drawing like characters of reference indicate corresponding parts in the several figures.

On the front of the door 1 I permanently 50 mount a somewhat elliptical shaped block 2 and above this I locate a case 3 of fanciful shape, the case presenting a dial 4 having

the hours indicated thereon and being provided with a central spindle 5 supplied with a pointer 6. Inside the door the spindle is 55 fitted with a finger piece 7 and a pointer 8, the pointer operating over a further time dial 9, the arrangement being such that both pointers will indicate the same time when turned by the occupant of the house. Obviously, by manipulating the finger piece 7 one can set the indicator or hand 6 to show a fixed time, which time will indicate when the party will return.

The block 2 has the front face thereof 60 gouged out to provide a front cavity 10 in which I mount a sign board or plate 11, the ends of the plate terminating in end spindles 12 and 13 rotatably mounted in the ends of the block. The plate is designed to normally close the entrance to the cavity and the cavity is provided to allow the plate to rotate. On one side of the plate I print the word "Out" and on the other side the word "In," with a result that one, by observing 70 the plate, can determine whether the occupant is in or out. Centrally the plate is provided with a stop lug 14 adapted to enter receiving notches 15 and 16 provided in the block and limit the swing of the plate.

The plate is controlled and manipulated 75 from the interior of the door by the parts now described.

On the spindle 13 of the plate I mount 80 a pulley 17 which is suitably pocketed within the block and is protected by a guard plate 18. To the back of the door I secure a bearing plate 19 which carries an opposing pair of lugs 20 and 21, the lugs supporting a pin 22 on which I mount rotatably a 85 further pulley 23. An elongated thimble like cap 24 is attached to the back of the plate 19 and encloses the latter pulley and houses a coiled spring 25, one end of which is seated at the base of the lugs and the other 90 end of which is connected to a push pin 26 which is provided at its outer end with a knob 27 and is supplied with a contracted neck 28 adjoining the knob.

The push pin passes slidably out through 100 a key hole slot 29 provided in the cap and the neck of the pin 26 is designed such that the pin can be locked in its inner position by entering the neck in the slot. The spring

normally acts to push the pin outwardly. To the inner end of the pin I connect a flexible line 30 which passes outwardly to and around the pulley 17, then inward and 5 around the pulley 23 and finally extends downwardly at the inner side of the plate 19 where it is attached to a coiled spring 31, the lower end of which is suitably anchored to the plate. The latter spring is housed 10 within a suitable casing 32. The spring 25 is considerably stronger than the spring 32 and in its extended position, such being when the pin 26 is out, holds the spring 31 extended, the line being taut.

15 The plate 11 is set such that when the push pin is out the plate exposes, at the outer side of the door, the word "In." By properly arranging the parts the pushing in of the pin 26 will cause the pulley 17 to 20 rotate one half revolution, with the result that the plate 11 is rotated a corresponding amount and the word "Out" is exposed.

In connection with the operation of the pulleys I might explain that when the push pin is forced inwardly by the finger, the 25 spring 25 is forcibly collapsed and the spring 31 takes up the slack in the line. Consequently, the pulley 17 is rotated. Upon the push pin being released, however, the 30 spring 25 pulls the line as it is stronger than the spring 31. This arrangement is an extremely simple and positive one and operates very satisfactorily.

I also embody a bell 33 with my 35 annunciator, the bell being mounted on the inside of the door on the plate 19 and being operated by a spring pressed push knob 34, exposed at the outer side of the door. The bell indicated is of the well known type embodying a spring which can be wound up 40 by turning the bell gong and has the hammers normally locked but adapted to strike the gong of the bell when released.

I have not considered it necessary to enter into a detailed description of the bell 45 parts but herein show how the push knob controls the bell. A push bar 35 is associated with the push knob 34 and passes slidably through the door and is formed 50 with a head 36 presenting an inclined face 37 and terminates in a finger trip 38. A sliding plunger 39 rides the face 37 and has the upper end engaged by a spring 40 suitably fastened to the bell frame. This 55 spring engages with the arm 41 of the bell hammer 42, and in the forward position of the push knob, locks the hammer against movement. Upon the push knob, however, being pushed inwardly the plunger forces 60 the spring 40 upwardly and releases it from the hammer arm. The hammer arm carries the escapement 43 of the bell mechanism and when the hammer arm is released the hammer strikes the gong.

65 It will be apparent that this device will

be of considerable value for one to indicate to the public when he is in or out, and if out, to give the public the definite time of his return.

Obviously, if the plate 11 is set to indicate "In" the setting of the hand 6 is of no consequence. The bell is provided as part of the equipment so that it can be used when the sign plate indicates that the party is in. 75

What I claim as my invention is:

1. In an annunciator for a door or such like, a frame secured to the outer side of the door, a plate having the ends thereof rotatably mounted in the ends of the frame 80 and having signals appearing on the opposite faces thereof, a pulley attached to one end of the plate, an endwise shiftable operating member located at the inner side of the door, a spring associated with the operating member, a pulley mounted on the inner side of the door, a flexible line having one end secured to the operating member and then extending around the former pulley and subsequently around the latter pulley and a tension spring having one end anchored and the other end secured to the free end of the line. 90

2. In an annunciator for a door or such like, a frame secured to the outer side of the door, a plate having the ends thereof rotatably mounted in the ends of the frame 95 and having signals appearing on the opposite faces thereof, a pulley attached to one end of the plate, an endwise shiftable operating member located at the inner side of the door, a spring associated with the operating member, a pulley mounted on the inner side of the door, a flexible line having one end secured to the operating member 100 and then extending around the former pulley and subsequently around the latter pulley, a tension spring having one end anchored and the other end secured to the free end of the line and means for releasably locking the operating member in a fixed position and with one of the plate signals exposed. 105

3. In an annunciator for a door or such like, a frame permanently secured to the outer face of the door, a plate having the ends thereof provided with pivot pins such pivot pins being rotatably mounted in the ends of the frame and the said plate having signals on the opposite faces thereof, a roller 115 secured to one end of the plate and suitably housed within the frame, a second roller located at the inner side of the door, a coiled spring secured to the door and surrounding the latter roller, a cap housing the spring 120 and provided with a key hole slot, a push pin secured to the spring and operating within the key hole slot, said push pin having a contracted neck permitting of the locking of the pin within the slot, a pulling 125 130

line secured to the push pin and extending around the former pulley and then around the latter pulley, and a coiled spring having one end anchored and the other end attached to the free end of the pulling line, said latter spring being weaker than the former spring and said pulling line being arranged in respect to the pulleys such that one or other of the signals on the plate is

exposed in the locked or free positions of the ¹⁰ push button.

Signed at Winnipeg, this 16th day of February, 1924.

RITUMA TACHIBANA.

In the presence of—

GERALD S. ROXBURGH,
M. B. KELLEHER.
